UNITED STATES PATENT OFFICE.

WILLIAM S. SHARPNECK, OF CHICAGO, ILLINOIS, ASSIGNOR OF TWO-THIRDS
TO EVERETT W. BROOKS AND JOHN D. ROSS, OF SAME PLACE.

GAS-ENGINE.

SPECIFICATION forming part of Letters Patent No. 626,124, dated July 4, 1899.

Application filed September 15, 1898. Serial No. 691,029. (No model.)

To all whom it may concern:

Be it known that I, WILLIAM S. SHARPNECK, a citizen of the United States, residing at Chicago, in the county of Cook and State of Illinois, have invented a certain new and useful Improvement in Gas-Engines, of which the following is a specification, references being had to the accompanying drawings.

This invention is an improvement on the style of engine shown in my applications, Serial Nos. 688,381 and 689,430, filed, respectively, August 11 and 23, 1898, and is intended to make an engine of this class which will be cheaply built, durable in wear, and easily managed.

To these ends the invention consists in the peculiar construction, arrangement, and combination of parts hereinafter more particularly described and then definitely claimed at the end hereof.

In the accompanying drawings, Figure 1 is an elevation of an engine constructed according to my invention with parts represented as broken away. Fig. 2 is a horizontal longitudinal section of the same, taken through the center of the cylinder. Fig. 3 is a similar section with the piston in a different position. Fig. 4 is a vertical section through the line $x-x$, Fig. 2, with some of the parts diagrammatically represented. Fig. 5 is a similar section, but with parts in another position. Fig. 6 is a similar section through the opposite trunnion and bearing. Fig. 7 is a similar section of a trunnion for a reversible engine.

Referring now to the details of the drawings by numerals, 1 indicates the base, of any approved form, provided with pillow-blocks 2, in which is mounted the crank-shaft 3 and to whose wrist-pin 4 is connected the hollow piston 5 by the piston-rod 6. The piston has an inlet-port 7 and an exhaust-port 8, which register at appropriate times with the inlet-port 9 and the exhaust-port 10 of the cylinder 11, which latter is provided with suitable trunnions 12 13 and oscillates in the bearings 14 15, rising from the base 1. The cylinder is cast double, so as to provide space 16 around it to form a water-jacket. In the trunnions 12 on the near side of the engine the inlet-port 9 is formed, whose outer end communi-

cates with the chamber 17, as shown in Fig. 5, in which is set the inlet-pipe 18. The exhaust-port 10 is formed in the opposite trunnion 13, and its outer end terminates in a long narrow opening, as indicated in Figs. 1 and 4, in order that the exhaust may be rapidly cut off by the oscillation of the cylinder. This port registers at the appropriate time with the port 19, as shown in Fig. 3, which then allows the exhaust to pass into chamber 20 and from thence out through the pipe 21.

Any suitable igniting apparatus may be used; but I show one similar to those indicated in my aforesaid applications, consisting of a suitably-insulated electric wire 22, passing through the filling-block 23 and terminating in a spring 24, which is touched as the engine operates by the contact-piece 25 on the piston to complete the circuit and which when separated by the motion of the piston creates a spark, and thus ignites the charge.

It is believed that the above description of the construction is sufficient to explain its operation; but in order that its operation may be evident to the meanest capacity the following brief description is given: Supposing the engine to be connected with gas and a source of electricity, the engine turning in the direction indicated by the arrow in Figs. 1 and 4, and that the gas has just been exploded, as the cylinder arrives in the position indicated at Fig. 3 the crank will be at the position 30 on Fig. 4, which will make the port 10 register with the port 19, and as the piston-port 8 registers at the same time with the port 10 the burned charge has free exit. As the crank continues its motion the communication between the exhaust-ports is broken, and thus a partial vacuum is formed in the piston and cylinder, and as the crank reaches the position 31 the inlet-ports register, as shown in Fig. 2, and the charge rushes in to fill the vacuum. As the engine still further continues its motion the crank reaches the place marked 32, which will bring the port 10 in the position indicated in Fig. 5, so that there is no exhaust, and the charge continues to be compressed and is exploded by the forming of the electric spark as the pis-

ton starts to return, when the above operations are repeated.

It is obvious that, like the engines shown in my previous applications, the engines may be made reversible by the use of a second exhaust-port 26 (see Fig. 7) in the bearing and a valve 28 to cover up one or the other of the exhaust-ports, as indicated in said Fig. 7, according to which way it is intended the engine should run.

What I claim as new is—

1. The combination in an engine, of an oscillating cylinder 11 having inlet-port 9 and exhaust-port 10 in the trunnions thereof, bearings for said trunnions having ports 17 and 19 communicating at appropriate times with the ports 9 and 10, and the piston 5 having a chamber open at one end communicating with the ports 9 and 10, at suitable parts of its stroke, substantially as described.

2. The combination in an engine, of an oscillating cylinder having an exhaust-port near the center of its length with a piston working in said cylinder having a port registering with said exhaust-port at about the center of its stroke, and means for closing the exhaust-port by the motion of the cylinder, substantially as described.

3. The combination in an engine, of an os-

cillating cylinder having an inlet-port in one trunnion, and an exhaust-port in the other, of a hollow piston open at one end and working therein and provided with an exhaust-port registering with the exhaust-port of the cylinder at about the center of its stroke, and an inlet-port registering with said inlet in the trunnion, substantially at one end of the stroke, substantially as described.

4. The combination in an engine of an oscillating cylinder, having inlet and exhaust ports formed in the cylinder-trunnions, with a hollow piston open at one end and working in said cylinder provided with an exhaust-port, registering with the exhaust-port in the cylinder, a bearing for one of the trunnions having a port arranged to allow the burned charge to exhaust when the piston is traveling in one direction and to close the exhaust when it is traveling in the other, substantially as described.

In testimony whereof I affix my signature, in the presence of two witnesses, this 13th day of September, 1898.

WILLIAM S. SHARPNECK.

Correction in Letters Patent No. 628,124.

It is hereby certified that in Letters Patent No. 628,124, granted July 4, 1899, upon the application of William S. Sharpneck, of Chicago, Illinois, for an improvement in "Gas-Engines," an error appears in the printed specification requiring correction, as follows: Page 2, lines 33-34 the compound word "exhaust-post" should read *exhaust-port*; and that the said Letters Patent should be read with this correction therein that the same may conform to the record of the case in the Patent Office.

Signed, countersigned, and sealed this 18th day of July, A. D., 1899.

[SEAL.]

Countersigned:

C. H. DUELL,
Commissioner of Patents.

WEBSTER DAVIS,
Assistant Secretary of the Interior.
